Charles Volkheimer, New Hyde Park, N. Y.

Application May 25, 1950, Serial No. 10,149

Term of patent 3½ years

(Cl. D54—16)

To all whom it may concern:

Be it known that I, Charles Volkheimer, a citizen of the United States, residing at New Hyde Park, Nassau County, New York, have invented a new, original, and ornamental Design for an Adjustable Ratchet Wrench, of which the following is a specification, reference being had to the accompanying drawing, forming a part hereof.

Fig. 1 is a top plan view of an adjustable ratchet wrench embodying my new design.

Fig. 2 is a bottom plan view.

Fig. 3 is an elevational view of the left side with the lower portion of the handle broken away.

Fig. 4 is an elevational view of the right side with the lower portion of the handle broken away.

Fig. 5 is an elevational view of the left end.

I claim:

The ornamental design for an adjustable ratchet wrench, as shown and described.

CHARLES VOLKHEIMER.
